Patented June 27, 1922.

UNITED STATES PATENT OFFICE.

L B HENRY BIXLER AND WILLIAM L. BIXLER, OF FRESNO, CALIFORNIA.

GARMENT CONVEYER.

1,420,907.

Specification of Letters Patent. Patented June 27, 1922.

Application filed December 10, 1920. Serial No. 429,757.

To all whom it may concern:

Be it known that we, L B HENRY BIXLER and WILLIAM L. BIXLER, citizens of the United States of America, and residents of 5 Fresno, in the county of Fresno and State of California, have invented certain new and useful Improvements in Garment Conveyers, of which the following is a specification.

This invention relates to combined elevators and receivers for clothes hangers, the 10 said invention having for its object the provision of novel means whereby hooks of clothes hangers may be engaged for carrying the said hanger with its contents from one 15 floor to another; novel means being provided whereby the hooks of the hangers are released from the carrier and supported with their loads in convenient position to be handled by an operator.

20 A still further object of this invention is to produce a novel hanger receiver associated with means for tripping or releasing the hooks of the hangers from the conveyer whereby the said hooks may be deposited on 25 the hook receiving arm.

With the foregoing and other objects in view, the invention consists in the details of construction and in the arrangement and combination of parts to be hereinafter more 30 fully set forth and claimed.

In describing the invention in detail, reference will be had to the accompanying drawings forming part of this specification wherein like characters denote corresponding 35 parts in the several views, and in which—

Figure 1 illustrates a perspective view of a conveyer system embodying the invention;

40 Figure 2 illustrates a view in elevation of elevator and receiver on a reduced scale; and

45 Figure 3 illustrates a perspective view of a fragment of the conveyer belt and hanger support.

In these drawings 5 denotes an approximately horizontally traveling conveyer belt or cord and 6 a guide or hanger therefor to be employed for carrying clothes hangers 7 having hooks 8 to different places on a floor of a building, but as the details of construction of this portion of the system are not dependent for its operation on the hanger elevating and depositing mechanisms, further 55 detailed description of the floor conveyer is omitted,

The present invention has more to do with the novel means for carrying clothes hangers from one floor to another and depositing the said hangers at a predetermined point or 60 points according to the position of the tripping mechanism, as will presently appear.

In carrying the invention into practice, a pulley 9 is mounted on a shaft 10, it being the purpose of the invention that the said 65 pulley shall rotate and that a conveyer belt 11 shall run thereover. An idler 12 is provided for the conveyer at its lower end and preferably the conveyer belt travels with relation to two sides of an upright 13, the said 70 upright having blocks 14 and 15 on one of its faces near its upper end in spaced relation to each other, the space therebetween being intended for the travel of the conveyer belt as it moves upwardly to the pulley 9. 75

The conveyer belt is provided with a plurality of hook engaging flanges 16, the said flanges being arranged in pairs and preferably formed integral with a plate 17 secured to the conveyer belt by fastenings 18 such as 80 rivets. The ends of the flanges constitute supports or engagements for the hooks of the clothes hangers 7 and the space between each pair of flanges 16 constitutes a clearance in which a roller 19 enters as the flanges and 85 plate are carried past the said roller. The roller 19 is mounted on an arm 20 extending upwardly and outwardly from a post 21 and this arm is intended to receive and hold the hangers as they are dislodged from the carrying flanges in passing the roller. It is shown in the drawing that the arm 20 is of 90 such length as to hold the roller 19 in a position nearly under the shaft 10 so that as the conveyer belt travels upwardly, it is approximately parallel with the upright 13 until after the roller 19 is passed. The conveyer belt then travels obliquely to the point with its engagement with the periphery of the pulley and then it travels around the 100 pulley as is usual with conveyer belts. 95

As the plates having the flanges reach the periphery of the pulley 19, they are tilted from a vertical to an oblique position in which position they cause the hooks of the 105 hangers to be dislodged and the said hangers therefore descend and are caught by the arm 20 down which they gravitate resting one against the other as they are progressively dislodged from the carrier, and an operator 110 may then distribute them to the room conveyers, one of which is shown and identified

by the numeral 5 or the hangers may be otherwise disposed of.

By suitably proportioning the pulley, an arm 20 can be provided at each floor and the 5 conveyer belt could be made to operate in conjunction with a plurality of floors by having a receiving arm at each floor movable into and out of operative relation with the conveyer belt. To that end, each arm 10 would be hinged as shown at 22 in order that it may swing clear of the conveyer belt or into engagement therewith. When in engagement with the conveyer belt it would preferably be held in position by a brace 23 15 movably mounted as at 24, and the said brace could then be moved into and out of operative engagement with the arm.

We claim:

1. In an elevator for clothes hangers, a 20 shaft, a pulley thereon, a conveyer belt operating over the pulley, hanger carrying elements attached to the conveyer belt, an arm projecting upwardly and diagonally, a roller mounted on the outer end of the arm 25 adapted to engage the conveyer belt, the said arm extending under the pulley to deflect the travel of the conveyer belt from a straight course whereby the hanger carriers are tilted as they pass the roller.
2. In a clothes hanger elevator and de- 30 positor, a pulley, an upright thereunder, blocks in spaced relation to each other

attached to one face of the upright, a conveyer belt, plates having parallel flanges in spaced relation to each other attached to the 35 conveyer belt, an arm extending upwardly and diagonally with relation to the conveyer belt, a roller on the outer end of the arm embraced by the flanges of the plates in their travel past the roller, the said roller 40 extending under the pulley for deflecting the conveyer belt, and hangers having hooks engaging the hanger supports and adapted to be dislodged therefrom when tilted by the roller.

3. In a clothes hanger elevator and depositor, a pulley, an upright thereunder, blocks in spaced relation to each other attached to one 45 face of the upright, a conveyer belt, plates having parallel flanges in spaced relation 50 to each other attached to the conveyer belt, a pivotally mounted arm extending upwardly and diagonally with relation to the conveyer belt, means for holding the arm in operative position, a roller on the outer 55 end of the arm embraced by the flanges of the plates in their travel past the roller, the said roller extending under the pulley for deflecting the conveyer belt, and hangers having hooks engaging the hanger supports 60 and adapted to be dislodged therefrom when tilted by the roller.

L B HENRY BIXLER.
WILLIAM L. BIXLER.
